VALVE MEANS FOR HYDRAULIC DOOR CLOSER
Elbert M. Spencer, Wildwood, Ill., assignor to The Illinois
Lock Co., a corporation of Illinois
Filed Apr. 15, 1964, Ser. No. 359,919
7 Claims. (Cl. 16—52)

This invention relates to hydraulic piston and cylinder type door closers and more particularly to a new and improved valve means therefor.

In a hydraulic piston and cylinder door closer, as for example, that shown in Gray et al. Patent 3,078,499, a piston moves in a cylinder which has a hydraulic fluid therein. As the door is opened, the piston is moved toward one end of the cylinder compressing a return spring. During this movement, the hydraulic fluid passes readily through or around the piston. When the door is released, the piston return spring urges the piston toward the other end of the cylinder, closing the door. A valve, as a check valve in the piston, closes causing the hydraulic fluid to flow only through a small metering passage, regulating the speed of door closing. In most cases, the metering passage is on the piston itself, and its size cannot be altered to change the door closing speed. There are structures known in which the hydraulic fluid passage is through the cylinder wall and can be regulated by a valve. However, this construction is relatively expensive.

It is therefore a general object of this invention to provide a new and improved valve means for a hydraulic door closer.

It is a primary object of this invention to provide a new and improved valve means for a hydraulic door closer which may be easily adjusted from the exterior of the door closer.

It is still another object of this invention to provide a new and improved valve means for a hydraulic door closer having means for selecting the size of an orifice through which the hydraulic fluid must flow during return of the door closer, which means may be easily adjustable from the exterior of the door closer.

Further objects and advantages will become apparent from the following detailed description taken in connection with the accompanying drawings, in which:

FIGURE 1 is a horizontal section view taken through a door and frame, and showing the door closer in use mounted to the frame and to an auxiliary door;

FIGURE 2 is a fragmentary enlarged section view of a portion of a door closer showing the valve means of this invention and illustrating the position of the several components as the closer is moved to a door closing position;

FIGURE 3 is a fragmentary enlarged view similar to FIGURE 2 and illustrating the position of the several components as the closer is moved to a door opening position;

FIGURE 4 is a section view taken along the line 4—4 of FIGURE 3; and

FIGURE 5 is a fragmentary enlarged view of the ratchet disc of the valve means of this invention.

While this invention is susceptible of embodiment in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

Referring now to the drawings, in FIGURE 1 the door closer 10 of this invention is shown mounted in a door frame generally indicated 12. A storm door 14

2

is hinged to the frame at 16. The door closer 10 includes a cylinder 18, a mounting means 20 at one end of the cylinder for securing the closer to the door frame and a piston rod 22 at the opposite end which is secured to the storm door 14 by means of door bracket 24.

The cylinder 18 is a substantially tubular circular cylinder and the piston rod 22 is slidably mounted in the cylinder on an axis generally coincident with the axis of the cylinder. The end of the rod nearest the mounting means 20 is provided with a piston 26 which includes the valve means of this invention. A spring 28 normally bears against the back side of the piston and urges the piston toward the mounting means 20 or a position of closure wherein the door 14 is maintained closed. The interior of the cylinder 18 is partially filled with a hydraulic fluid (not shown).

In operation, as the door 14 is swung about its hinge, the rod 22 slides outward relative to the cylinder in opposition to the spring 28. Hydraulic fluid flows freely, 20 in a manner to be explained in detail later, from that side of the piston where the spring is located to the opposite side of the piston. When the rod reaches a point wherein the force of opening the door is overcome by the force of the compressed spring, the spring urges the 25 piston toward the other end of the cylinder in opposition to the hydraulic fluid. The hydraulic fluid then travels back through the piston in a controlled fashion, as will be explained in detail later, to cause the door to return to a position of closure at a controlled rate.

30 The piston 26 incorporates the valve means of this invention. The piston includes a piston washer 30 which is fixed to a reduced or stud end 22a of the rod 22. The washer is provided with a circular flanged end 32 having a plurality of fluid passages 34 therein, an intermediate 35 reduced diameter boss portion 36 and an inwardly facing reduced diameter mounting boss portion 38. Mounted about the outer periphery of the mounting boss 38 concentric to the rod is an orifice disc 40. Orifice disc 40 is a washer-like disc having an inner diameter slightly 40 larger than the outer diameter of the boss 38 so that the orifice disc is free to rotate relative to the washer 30 and, therefore, the rod 22. The periphery of the orifice disc is provided with a pair of opposed inwardly facing arms 42 which extend away from the washer 30 generally perpendicular to the face of the orifice disc and parallel to the axis of the cylinder only slightly spaced from the inner wall of the cylinder. The face of the orifice disc is provided with a plurality of different sized fluid passages 44 of different diameter, such as 44a, 44b and 44c and so on disposed in a ring concentric to the rod.

45 Positioned between the orifice disc and the washer 30 is an O-ring 46 which seals the gap 29 between the piston structure and the inner wall of the cylinder as the piston moves to and fro within the cylinder. When the rod is returning to a position of closure and the piston and rod are moving in the direction of the arrow A in FIGURE 2 (to the left in the drawing), the O-ring moves, under the influence of the hydraulic pressure, 50 against the orifice disc and seals the gap between the arms and the inner wall of the cylinder to prevent hydraulic fluid from passing through the gap. When the piston rod is moving to a position of extension wherein the door is being opened, as indicated by the arrow B in FIGURE 5 (to the right in the drawing), the O-ring moves against the face of the washer 30 under the influence of the hydraulic pressure to seal the gap between the periphery of the washer and the inner wall of the cylinder.

55 Positioned about the stud end of the rod inwardly of the washer and orifice disc is the valve disc 50. The valve disc is also fixed to the stud end of the rod so that both the washer 30 and the valve disc 50 rotate with

the rod 22 and relative to the orifice disc 40 when the rod is rotated. The valve disc is provided with a single elongated arcuate slot 52 located on a radius which is in concentric alignment with the several orifice passages 44. The valve disc is further provided with an inwardly projecting boss 54 having radially extending facial deformations forming an indexing surface 56 affording an indexing means for insuring alignment of one of the openings 44 with the slot 52 to provide a fluid passage through the orifice and valve discs.

Spaced inwardly from the valve disc is the disc 58 which has an outwardly projecting boss 60 opposing the boss 54 of the valve disc and an indexing surface (not shown) for mating with the indexing surface 56. Disc 58 has an inner diameter which is slightly larger than the outer diameter of the rod so that the rod may rotate relative to disc 58. Opposed notches 62 are provided in the periphery of the ratchet disc for receiving the arms of the orifice disc. The notches 62 are slightly larger than the cross sectional dimension of the arms 42 to permit fluid flow through disc 58 to the opposite side of the piston.

The face of disc 58 opposite the boss 60 is provided with a pair of outwardly projecting spaced studs 66. The free end of the spring 28 is held between these studs. As the rod is rotated to turn the valve disc 52, disc 58 remains fixed relative to the rod due to the slip-fit of the disc 58 relative to the rod as well as the force of the spring 28 which tends to prevent rotational movement of the disc. Because the orifice disc 40 is joined to the disc 58 by the arms 42 it too is held against rotation by the spring 28.

The free end of the piston rod is slotted at 64 at a point outside the cylinder so that it is engageable by suitable means, such as a screw driver. By engaging a screw driver in the slot and turning the rod, the valve means of this invention is adjusted to meter the flow of fluid and adjust the rate of return of the rod. Turning of the rod causes the washer 30 and valve disc 50 to turn relative to disc 58 which, through engagement with the orifice disc arms 42 holds the orifice disc stationary relative to the rod and the valve disc to bring a selected opening 44 opposite the slot 52. Depending upon whether a faster or slower rate of return is desired, a larger or smaller sized opening 44 will be positioned opposite the slot 52. The indexing surfaces on the valve disc and disc 58, which are continually urged together by spring 28, are appropriately mated so that seating is accomplished only when one of the openings 44 is opposite the central portion of the slot 52 in the valve disc.

In operation, as the door 14 swings open and closed and the rod moves to and fro in the cylinder, hydraulic fluid will pass from one side of the piston 26 to the other through the openings 34 in the washer, openings 44 in the slot 52 in the valve and through the spaces between the notch 62 and the arms 42. When the rod is traveling to a position of extension wherein the door is being opened, as indicated by the arrow B in FIGURE 3, the O-ring 46 moves against the inner face of the washer 30. This permits the hydraulic fluid to flow around the piston between the arms 42 and the inner periphery of the cylinder 18. The O-ring blocks the continuation of this flow so that the fluid is diverted around the O-ring and is shunted through the several openings 34 in the washer 30.

When the rod is traveling to a position of return as indicated by the arrow A in FIGURE 2, the O-ring moves against the outer face of the orifice disc. After the O-ring moves against the orifice disc continued movement of the rod to the return position will cause the orifice disc to move against the valve disc. Hydraulic fluid passing through openings 34 and 44 will then be confronted with the valve disc 50. The valve disc is provided with the single arcuate slot 52 so that the amount of fluid passing through the slot 52 can be metered by the selec-

tion of an appropriately sized opening 44 opposite the slot 52 to change the rate of return of the rod. Once past the valve disc 50, the fluid flows through those portions of the slot 62 not occupied by the arms 42 to the opposite side of the piston.

The valve means of this invention affords an externally actuatable means for adjusting the rate of flow of hydraulic fluid in a hydraulic door closer, while retaining the basic simplicity of construction normally found in such devices. The valve means is incorporated as a part of the piston and is comprised of relatively simple disc-like components which may be easily manufactured and assembled. Adjustment is accomplished by means of a screw driver or similar instrument inserted in the notched end of the piston rod for turning the same, a relatively simple operation. Observation of door movement will determine whether the selected orifice 44, which has been placed opposite the slot 52, satisfactorily meters the flow of hydraulic fluid to obtain the desired rate of return. If not, then the rod 22 need only be turned once again or until the proper one of the several openings 44 is positioned opposite the slot 52 to obtain the optimum rate of return. Thus, the valve means of this invention solves a problem in the hydraulic door closer art which solution involves simplicity of structure as well as operation thereby enhancing the reliability and economy of the device.

I claim:

1. An adjustable valve means for a hydraulic door closer having a cylinder containing hydraulic fluid, a rod in said cylinder slidable in the cylinder between a position of extension and a return position of closure, and a spring urging the rod toward the position of closure, comprising: first and second valve members mounted about said rod for movement relative to each other, one of said valve members being mounted for movement with said rod, said first valve member having fluid passage means therein and said second valve member having a plurality of different sized fluid passage openings therein; and cooperating indexing means associated with said first and second valve members for aligning the openings of said members so that turning of said rod will move said members relative to each other to align said first member passage means with a second member opening to adjust the rate of flow of hydraulic fluid through said valve members as said rod moves in opposition to said fluid to the position of closure.

2. The valve means of claim 1 wherein said valve members are discs concentrically mounted on said rod and said discs rotate relative to each other when said rod is rotated to align the openings in the discs.

3. The valve means of claim 1 wherein said first valve member has one enlarged opening and said second valve member has a plurality of different sized openings each of which is smaller than the opening in said first valve member.

4. A hydraulic door closer, comprising: a cylinder having hydraulic fluid therein; a rod in said cylinder mounted for movement between positions of extension and a position of closure; a spring in said cylinder normally urging said rod to one end of said cylinder to a position of closure; a piston on said rod having means for adjusting the rate of return of said rod to a position of closure in opposition to said fluid, said piston including a first washer having a flange and an inwardly projecting boss portion and secured to said rod about said boss portion; a first valve disc loosely mounted about said boss portion and having a plurality of different sized fluid passage openings therethrough, said first valve disc being further provided with a pair of inwardly facing arms, a second valve disc fixed to said rod adjacent said first valve disc provided with a single fluid passage therethrough and further provided with an inwardly projecting boss having radially extending facial deformations forming an indexing surface thereon, and a third disc loosely mounted about

said rod spaced from said second valve disc and provided with an outwardly facing boss having an indexing surface mating with said second valve disc indexing surface, said third disc being fixed to one end of said spring and having means for receiving the arms for said first valve disc so that turning of said rod turns said second valve disc relative to said first valve disc to place the fluid passage in said second valve disc opposite one of the fluid passages of the first valve disc to adjust the rate of flow of hydraulic fluid through said valve member as said rod returns to the position of closure and thereby adjust the rate of return of said rod.

5. In a hydraulic door closer, including a cylinder adapted to contain hydraulic fluid, a rod in said cylinder slidable between a position of extension and a position of return and a spring urging said rod toward the position of return, valve means for adjusting the rate of return of said rod, comprising: a piston including a group of first valve members fixed to the rod for rotation therewith and a group of second valve members loosely associated with the rod to be non-responsive to rotation of the rod, said valve members having means establishing fluid passages therethrough with one of said members having fluid passages of different sizes for adjusting the rate of fluid flow through the piston by positioning said one member so that selected fluid passages are in alignment with the fluid passages in the other members; means securing said spring to one of the second group of valve members to hold that group fixed as the rod and first group of valve members is rotated and indexing means for aligning the openings of the several members as the rod is rotated including cooperating indexing surfaces on one of the members of said first group and one of the members of said second group.

6. The hydraulic door closer of claim 5 wherein the members of the second group are held against rotation by finger means bridging a member of the first group and extending into engagement with the member of the second group which is secured by said spring.

7. In a hydraulic door closer including a cylinder adapted to contain hydraulic fluid, a rod in said cylinder slidable between a position of extension and a position of return, and a spring urging said rod toward the return position, valve means for adjusting the rate of flow of hydraulic fluid, comprising: a piston of first and second relatively rotatable valve members having means forming a fluid passage therethrough, one of said valve members having openings of different sizes therein constructed and arranged to be generally aligned with an opening in the other member to change the flow of fluid through said piston, said first member connected to said rod for rotational movement therewith as said rod is rotated, said second valve member joined to means having locking surfaces in engagement with said spring and held thereby against rotational movement with said rod whereby the rate of flow of hydraulic fluid through said piston may be adjusted by rotating said rod; and indexing means associated with said first and second valve members for maintaining alignment of the fluid passages in said members after the rod is rotated.
